(57) **CLAIM**

The ornamental design for a lamp for head, as shown and described.

DESCRIPTION

FIG. 1 is a perspective view of a lamp for head showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

(Continued)

The broken lines in the drawings illustrate portions of the lamp for head that form no part of the claimed design.
